GRILLING APPARATUS

William M. Bardeau, 44 Princess Margaret Blvd.,
Islington, Ontario, Canada

Filed Sept. 5, 1972, Ser. No. 286,472

Claims priority, application Canada May 1, 1972

Term of patent 14 years

Int. Cl. D7—02

U.S. Cl. D7—88

FIG. 1

FIG. 2

FIG. 3

FIG. 4

FIG. 5

FIG. 1 is a perspective view of the grilling apparatus taken from a point to the front and slightly upwards to the left thereof;

FIG. 2 is a perspective view of the grilling apparatus of FIG. 1 taken from a point to the rear and slightly above to the left;

FIG. 3 is a perspective view of the grilling apparatus of FIG. 1 from the same vantage point, but with the cover in the raised position;

FIG. 4 is a side elevational view of the grilling apparatus of FIG. 1 taken from the right side;

FIG. 5 is a front elevational view of the apparatus of FIG. 1; and

FIG. 6 is a plan view of the grilling apparatus of FIG. 1.

I claim:

The ornamental design for a grilling apparatus, as shown.
